UNITED STATES PATENT OFFICE.

ARTHUR M. PADMORE, OF LEAD, SOUTH DAKOTA.

RACK.

SPECIFICATION forming part of Letters Patent No. 784,499, dated March 7, 1905.

Application filed July 8, 1904. Serial No. 215,809.

To all whom it may concern:

Be it known that I, ARTHUR M. PADMORE, a citizen of the United States, residing at Lead, in the county of Lawrence and State of South Dakota, have invented new and useful Improvements in Racks, of which the following is a specification.

This invention relates to a rest for supporting table accessories—such as a knife, fork, and spoons—and is designed to be placed in front of each plate at table to receive one or more of the articles mentioned, and especially in the case of the knife and fork to keep them elevated above the table-cloth, and so avoid soiling it.

It is well known that many persons are uncertain what to do with their knives and forks when called upon to pass their plates for food. Some hold their knives and forks in their hands; others leave them on their plate; others, again, place them on the table, and thereby soil the cloth; but by the use of my invention all uncertainty in regard to the disposition of the knife and fork is avoided, and the diner is placed at ease.

In the accompanying drawings, Figure 1 is a perspective view of my improved rest, with a knife, fork, and two spoons shown in dotted lines as supported thereon. Fig. 2 is a plan view of the rest.

Similar numerals of reference are employed to indicate corresponding parts in both views.

The numerals 1 and 2 indicate two curved side bars united at their ends to form feet 3. Each side bar is of substantially ogee form, so placed with respect to each other that the greatest distance between them is about intermediate their connected ends, at which place an angularly-disposed cross-brace or supporting-plate 4 is connected to each bar. The bars 1 and 2, which are higher at the cross-bar connections than at their ends, descend from these higher points in curved and other ornamental lines to the feet 3. Feet 5 depend from the highest part of the bars 1 and 2 to give additional support to the rack and prevent it from tilting. The upper edge of the cross-bar 4 is

provided with notches 6 and 7, formed by upwardly-extending fingers 8, 9, and 10 or by depressions in the cross-bar. Notches 11 and 12 are formed on the bar 1 between the cross-bar 4 and one of the feet 3 by upwardly and outwardly curved fingers 13 or by depressions in the bar similar to those on cross-bar 4. The bar 2 is provided with similar notches 11 and 12 between the cross-bar 4 and the other foot 3, the arrangement being such that the relative position of the notches in the cross-bar 4 to those in the bars 1 and 2 will be the same irrespective of the position of the rack.

When in use, the knife and fork are generally supported in the notches 11 and 12 in the front bar on the right of the rest and in the notches 6 and 7 in the cross-bar 4. The spoons rest in the notches 11 and 12 on the rear bar and at the left of the rack. It will thus be observed that a secure support is provided for the knife, fork, and spoons small of compass and compact in form.

The rack will be made ornamental and attractive and varied in shape more or less, as desired, provided the feature of reversibility with notched side and cross bars be retained.

It is to be understood that the word "notches" hereinabove used is to be taken in its broadest sense and includes a space between two projecting fingers.

Having thus described the invention, what is claimed as new is—

1. A rest for table use comprising two side bars united at their ends and separated intermediate thereof, a cross-bar centrally and angularly disposed between said side bars, and notches in said cross-bar and in opposite ends of each side bar.

2. A rest for table use comprising side bars provided with end portions diagonally disposed to the longitudinal axis of the rest and having their upper sides notched near their diagonally-disposed ends, and a diagonal cross-bar connecting each side bar and also provided with notches in its upper side.

3. A rest for table use comprising a supporting-frame formed of two ogee-curved side

bars with upwardly-opening notches in their opposite ends, and a cross-bar between said notched ends of the side bars and provided with similar notches.

5. 4. A rest for table use comprising two curved bars united at their ends and separated at their centers, a cross-bar between said side bars having upstanding fingers, fingers being also

formed on one end of each side bar diagonally opposite each other. 10

In testimony whereof I affix my signature in presence of two witnesses.

ARTHUR M. PADMORE.
